UNITED STATES PATENT OFFICE.

ALFRED H. RAMEY, OF AURORA, ILLINOIS.

INHALER.

SPECIFICATION forming part of Letters Patent No. 794,641, dated July 11, 1905.

Application filed March 6, 1905. Serial No. 248,599.

To all whom it may concern:

Be it known that I, ALFRED H. RAMEY, a citizen of the United States, residing at Aurora, in the county of Kane and State of Illinois, have invented certain new and useful Improvements in Inhalers; and I do declare the following to be a full, clear, and exact description of the invention, such as will enable others skilled in the art to which it appertains to make and use the same.

My invention is an improved inhaler adapted for use in treating diseases of the nasal passages, throat, bronchial tubes, and lungs by inhalation; and it consists in the construction, combination, and arrangement of devices hereinafter described and claimed.

In the accompanying drawings, Figure 1 is a perspective view of an inhaler embodying my improvements. Fig. 2 is a longitudinal sectional view of the same, and Fig. 3 is a transverse sectional view of the same.

In the embodiment of my invention I provide a container 1, of suitable size and shape, adapted to contain a sponge or other fabric saturated with a medicament, and said container is provided at one end with a closure 2, which is here shown as a screw-cap. From one side of the container projects a pair of discharge-tubes 3, which are of such size and 30 at such distance apart as to enable their upper ends to be readily placed in the nostrils of the patient. In one side of the container is an opening 4. A pipe 5 projects from a ring or band 6, which encircles the container at a point midway between the discharge-pipes 3 and which is provided with an opening 7 at the inner end of the pipe 5, which opening is adapted to register with the opening 4 in the container when the pipe 5 is 35 turned at about right angles with reference to the pipes 3, as shown in full lines in Fig. 3. When the said pipe 5 is turned to a position between the pipes 3, it is out of register with the opening 4, and hence does not communicate with the interior of the container. Suitable stops 8 are provided to limit the movement of said pipe 5.

In operation a suitable medicament is placed

in the container, and if the nasal passages are to be treated the patient inserts the pipes 5 or nipples 3 in his nostrils, places the pipe 5 in his mouth, and blows through the same, thus forcing out the warm air through the medicament in the container, whereby it becomes charged therewith, the warm air thus treated then passing up into the nostrils. When the bronchial tubes, throat, or lungs are to be treated, the pipes or nipples 3 are not placed in the nostrils; but the pipe 5 is placed in the mouth of the patient, and in breathing through the same the air carried into the lungs is caused to pass through the medicament in the container, and hence becomes medicated. When the device is not in use, the tube 5 is turned to a position between and in line with the pipes or nipples 3, where it is out of the way, and thus communication between the said tube and the interior of the container is cut off to prevent loss of the medicament.

Since the pipe 5 may be turned to any desired angle with respect to the pipes or cables 3, it will be understood that the inhaler may be adjusted to fit any person.

It will be understood that my improved inhaler may be made of wood, metal, glass, rubber, or any other suitable material.

From the foregoing description, taken in connection with the accompanying drawings, the construction and operation of the device will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

An inhaler comprising a cylindrical body portion open at one end and having a closure therefor, said body portion having an opening in one side and also provided with a pair of discharge-tubes projecting from one side thereof and adapted for insertion in the nos-

trils, a mouth-tube pivotally connected to the said body at a point between the nostril-tubes and adapted to be moved into and out of register with the opening on the side of the body portion, and means to limit the angular movement of the said mouth-tube, substantially as described.

In testimony whereof I have hereunto set my hand in presence of two subscribing witnesses.

ALFRED H. RAMEY.
